RAZOR BLADE DISPENSER

Edgar A. Nelson, New York, N. Y., assignor to
American Safety Razor Corporation, Brooklyn,
N. Y., a corporation of Virginia

Application April 7, 1949, Serial No. 1,855

Term of patent 14 years

(Cl. D52—2)

To all whom it may concern:

Be it known that I, Edgar A. Nelson, a citizen of the United States, and a resident of the city, county, and State of New York, have invented a new, original, and ornamental Design for a Razor Blade Dispenser, of which the following is a specification, reference being had to the accompanying drawing, forming part thereof.

Fig. 1 is a downward perspective view of a razor blade dispenser taken from the rear, showing my new design; and

Fig. 2 is a downward perspective view thereof taken from the front.

I claim:

The ornamental design for a razor blade dispenser, as shown.

EDGAR A. NELSON.
